UNITED STATES PATENT OFFICE.

ERNEST OWEN, OF NEW YORK, N. Y.

APPARATUS FOR CONDENSING AND FRACTIONATING HYDROCARBONS.

Application filed December 14, 1920. Serial No. 430,617.

To all whom it may concern:

Be it known that I, ERNEST OWEN, a citizen of the United States, and a resident of the city of New York, borough of Manhattan, in the county and State of New York, have invented new and useful Improvements in Apparatus for Condensing and Fractionating Hydrocarbons, of which the following is a clear and detailed description.

The apparatus relates more particularly to the distillation of petroleum and seeks for one of its principal objects to provide a means for effecting a more perfect separation of the hydro-carbons which are evolved as a body of mixed vapors from a still, into distinct fractions than has heretofore been accomplished.

The usual method now practiced by petroleum refiners, is to first condense the vapors from the still in one condenser, thus necessitating the rerunning of the condensate in other stills in order to separate it into the different marketable fractions. This procedure not only greatly increases the operating expense of the plant, but requires a large initial outlay in additional equipment. So far attempts that have been made to fractionate the vapors from the still have resulted in a more or less imperfect separation of the fractions, requiring redistillation in order to obtain the perfect fractions.

The present invention contemplates the fractionation of hydrocarbon vapors into distinct and clearly defined products, the specific gravity of which may be varied at the will of the operator by the regulation of the flow of the cooling medium through each condenser unit by means of automatic temperature controlling devices arranged in the vapor outlet from each condenser.

In order to economize in the amount of cooling water required, it is a further object of the invention to feed the water through the various units of the apparatus successively and concurrent to the flow of the vapors, whereby the water utilized in one condenser as it becomes heated may be utilized to cool fractions of a higher boiling point in the remaining units.

Furthermore, in order to insure that the product condensed in each unit will be of a homogeneous composition, there is provided in connection with each unit, a tower or column having means therein whereby should any lighter vapors than those desired be condensed, this lighter condensate in its passage through the tower will be re-evaporated by the ascending vapor and carried to the next unit.

The invention furthermore contemplates the provision of a separator disposed between each condenser and tower which is adapted to function to return the entrained liquid to the proper rectifying column in order to prevent any of the heavier condensed vapors from being mechanically picked up and swept over into the next unit by the rapidly moving vapors.

Furthermore, in order to vaporize the lighter fractions of the crude or charging oil to relieve the still of a certain amount of work, the invention contemplates the provision of means for initially subjecting the vapors from the still to a bath in the crude or charging oil supply whereby to vaporize and remove the lighter fractions from the crude oil supply without the necessity of passing the same through the still, the crude oil at the same time functioning to condense and remove from the vapor the heavier fractions in order that the same may be returned with the crude oil supplied to the still.

With the above recited and other ends in view, some of which will appear as the nature, purpose and operation of the invention is more fully understood from the following detailed description and the appended claims, reference is had to the accompanying drawings forming a part of this application, and in which;

Figure 1 is a side elevation of the complete apparatus.

Figure 2 is a fragmentary vertical sectional view through one of the units of the apparatus.

Figure 3 is an enlarged fragmentary detailed view of the automatic controlling means for the water cooling supply.

Figure 4 is a vertical sectional view taken approximately on the line 4—4 of Figure 2.

Figure 5 is a vertical sectional view through a modified form of one of the units 5 of the apparatus.

Figure 6 is a horizontal sectional view therethrough taken approximately on the line 6—6 of Figure 5.

Figure 7 is an enlarged detail fragmentary 10 sectional view through the rectifier tower illustrating the construction of the gravity spray nozzle employed in connection therewith.

Referring to the drawings by characters 15 of reference, the apparatus consists of a primary unit 10 and one or more secondary units 11, any number of which may be employed in connection therewith and coupled to each other in series. The primary unit 20 includes a stripping tower or column 12 having a vapor intake pipe 13 at its lower end which establishes communication between the same and a still or furnace for conveying the distillate or vapor therefrom 25 to the stripping tower. The primary unit also includes a reflux condenser drum 14 supported in superposed relation thereon and connected thereto by the conduit pipe 15. The secondary units 11 each include 30 a rectifying tower or column 16 and a pair of superposed drums 17 and 18 respectively constituting an exchange drum and a dephlegmator drum. The construction of the stripping and rectifying towers 12 and 35 16 are substantially identical and each comprises a plurality of vertically spaced horizontal walls 19 which divide the tower into an upper chamber 20, a lower chamber 21 and a plurality of intermediate chambers 40 22. The walls 19 are each provided with upstanding nipples 23 over which are arranged inverted cup-shaped caps 24 having the lower edges notched as at 25 whereby to provide means for trapping and maintaining a supply of liquid at a predetermined 45 level in the upper compartment 20 and each of the intermediate compartments 22. A vertical stand pipe 26 extends through each wall 19 and the upper extremity thereof is disposed slightly above the upper end of the nipples 23 to maintain the levels of the liquid exteriorly of the caps 24 slightly above the level of the liquid within the same. The lower extremity of 50 55 the stand pipe is disposed slightly below the upper extremity of the stand pipe of the compartment therebeneath, whereby said lower extremity will be immersed in the liquid supply thereof. By this arrangement 60 the vapors which enter the lower chamber 21 will pass upwardly through the nipples 23 and will be compelled to bubble up through the liquid to the chamber above until it finally reaches the upper compartment

ment 20. In the primary unit 10 a pipe 65 28 leads from the lower chamber to the still and constitutes a conduit for conveying the crude oil thereto. The pipe is bent as at 29 to provide a trap which functions to maintain the fluid at a constant level in 70 the lower chamber and at the same time operates to prevent the passage of vapor from the still to said lower chamber 21. The lower end of the lowermost stand pipe 75 26 is immersed in the fluid in the lower chamber 21 to prevent the passage of the vapor from the compartment 25 through the stand pipe and compel it to pass through the nipples 23. In the secondary units 11, a drain pipe 30 communicates with the lower chamber 21 and the same is provided with an offset portion 31 which functions to maintain a constant level of the fluid of condensation therein, whereby to seal the lower end of the lowermost pipe 26 for a 80 like purpose. In the primary unit the reflux condenser 14 is substantially of the same construction as the exchange and dephlegmator drums 17 and 18 of the secondary units 11. Each of the drums are 85 provided with outer heads 32 and inner heads 33 spaced therefrom to provide the end chambers 34 connected by a plurality of batteries of tubes 35 which extend through the central chamber 36 and establish communication between the chambers 34. The drums are further divided by the longitudinal partition walls 37 which extend alternately therethrough from the opposite outer heads 32 into the central chamber 36 and terminate short of the inner heads 33. By this arrangement it will be seen 90 that the vapor taken in at one side of the lower partition 37 in one of the outer chambers 34, will be compelled to travel through 95 the tubes to the opposite end chamber 34, in a sinuous course from the inlet to the outlet. It will be further evident that fluid taken into the central chamber at one side of one partition 37, will be compelled to 100 travel through a sinuous course around the tubes to and from the inlet to the outlet at the opposite side of the other partition. The outlet of the reflux condenser is connected by a conduit pipe 38 to the lower chamber 110 115 16 of the adjacent secondary unit 11. Likewise the outlet of the dephlegmator drum 18 of each secondary unit 11 is connected by conduit pipe 39 to the lower chamber 21 of the 120 rectifying tower of the next adjacent unit.

The initial supply of crude or charging oil is conveyed by a pipe 40 to the central chamber 36 of the last exchange drum 17 of the series of units thereby entering said central chamber above the upper partition 37, where it flows through said compartment and is carried off by a conduit pipe 41 which

enters the central chamber 36 to the next adjacent exchange drum after taking a sinuous course therethrough around the batteries of tubes 35. In each of the succeeding units the crude oil supply is conveyed through a similar pipe 41 to the next adjacent secondary unit 11. The crude oil is conveyed by a pipe 42 directly to the upper chamber 20 of the stripping tower 12 where it gravitates through the various nipples 23 and stand pipes 26 to the bottom compartment 21 and is finally carried to the still or furnace through the pipe 28. At the same time the vapor conveyed by the pipe 13 from the furnace is traveling through the stripping tower 12 to the reflux condenser 14 by way of the conduit pipe 15, which enters one of the end chambers 34 below the partition 37 at the lower side of the drum, the vapor traveling in a sinuous course through the tube batteries 35 to the outlet. The vapor from the reflux condenser passes into the lower chamber 21 of the rectifying tower of the adjacent secondary unit 11, repeating the action set forth in the stripping tower 12. From the upper chamber 20 of the rectifying tower 16 it is conveyed by a pipe 43 to one of the end compartments 34 of the exchange drum 17, below the partition 37 thereof thence through the tube batteries 35 to the opposite end compartment 34 and through a pipe 44 to the dephlegmator 18. During the sinuous course of travel through the exchange drum, it is evident that the crude oil flowing through the center compartment will tend to cool the vapor, while the vapor at the same time will function to heat the crude oil thereby setting up the exchange action. From the pipe 44 the vapor enters the dephlegmator 18 in one of the end compartments 34 below the lower partition 37 and thence through the tube batteries in a sinuous course to the opposite end compartment above the upper partition 37 to an outlet pipe 45 which is connected to the conduit pipe 39. In the dephlegmator drums 18 and the reflux condenser 14, the central chambers 36 constitute a compartment for the reception of the cooling agent, preferably water. A water supply line 46 traverses the series of units 11 and is provided with a three way valve 47 arranged therein adjacent each dephlegmator drum 18. A branch or feed pipe 48 leads from one port of each valve 47 to the chamber 36 of its respective dephlegmator, above the upper partition wall 37. An outlet and return pipe 49 communicates respectively with the chamber 36 at the bottom of the drum and the feed pipe whereby the cooling agent may be circulated therethrough. The supply line 46 connects with a three way valve 50 adjacent the reflux condenser and said valve communicates through a branch feed pipe 51 with the upper end of the chamber 36 of the reflux condenser. The remaining port of the valve 50 communicates with an exhaust water pipe 52 into which the outlet and return pipe 53 from the bottom of the reflux condenser drum 14, empties. Each of the three way valves 47 is provided with a shiftable valve member 47^a which is adapted to co-act with the respective valve seats 47^b and 47^c. By this arrangement upon the shifting of the valve, the water supply or cooling agent may be either circulated through the dephlegmator drums or reflux condenser drum, or by-passed around the same.

In order to provide means for rendering the apparatus automatic in its operation, a temperature controlling device is employed for actuating the valve, said mechanism being of any ordinary construction. In the particular showing made the automatic controlling device includes a diaphragm 54 which operates directly on the valve stem 55 when air is supplied thereto through the air pipe 56. A thermostatically actuated air valve 57 controls the supply of air through the air pipe 55 and the thermostatic tube 58 of said valve 57 enters the outlet pipe 45 where it will be subjected to the heat action of the vapors passing therethrough. An indicator dial 59 having an indicator and setting arm 60 is provided for setting the thermostatically controlled valve to any desired degree. When the temperature of the vapors reaches the predetermined degree desired, the thermostatic tube will actuate the air controlling valve 57 to shut off the air supply to the diaphragm 54, permitting a spring 61 to function to move the valve member 47^a into contact with the seat 47^c, to establish communication between the supply line 46 and the branch pipe 48. The water will then flow into the central chamber 36 of the dephlegmator and after circulating therethrough will flow through the outlet and return pipe 49, back to the supply line 46. Where the temperature falls below the predetermined degree of heat, the thermostatic tube will open the valve 57 to allow the supply of air to actuate the diaphragm and shift the valve member 47^a into contact with seat 47^b, whereby the water will be by-passed around the dephlegmators. The three-way valve 47 of the primary unit 10 operates in a similar manner for establishing communication between the reflux condenser 14, and the supply line. By this arrangement the water may be run through or by-passed around the reflux condenser under the controlling action of a similar controlling device.

In order to provide additional means for removing the heavier fractions from the vapor or gas during its travel from the reflux condenser to the rectifying column or from

the dephlegmators to the rectifier columns, use is made of the separators 66 which communicate respectively with the outlet pipe 45 and the conduit pipes 38 or 39. The separators are provided with a plurality of spaced baffle plates 67 depending from their upper wall and the lower wall of said separators receives the drain pipes 68 which carry off and return the heavier fractions to the stripping or rectifying tower as the case may be. Preferably traps 69 are arranged in the drain pipes 68 to seal the pipes against the passage of vapor or gas therethrough from the stripping or rectifying towers to the separators 66. The conveyor pipe 42 leading from the exchange drum 17 to the stripping tower is provided with a depending offset 70 which constitutes a trap to eliminate the possibility of the passage of the vapor from the stripping tower to the exchange drum.

In use and operation of the apparatus, vapor or gas generated in the still or furnace is conveyed by the pipe 13 to the lower chamber 21 of the stripping tower or column 12, from whence it rises through the nipples 23 to the caps 24 and through the liquid trapped in each of the intermediate compartments 22 and the upper compartment 20. The liquid contained in these compartments is a mixture of the crude or charging oil supplied thereto through the pipe 42 and the vapor condensate which is formed in the reflux condenser 14 and the separator 66. In passing through the liquid, the vapor will strip the lighter fractions from the crude or charging oil and carry said fractions with it. The vapor then passes to the reflux condenser drum 14, where the flow of the cooling water is so regulated by the automatic temperature controller as to condense and return to the still through the stripping tower 12, the fractions heavier than a predetermined gravity. Any heavier condensate mechanically carried by the vapors leaving the reflux condenser, is removed therefrom by the separator 66 and returned to the stripping tower by the drain pipe 68. The vapors leaving the separator will be conveyed by the pipe 38 to the lower chamber 31 of the first rectifying tower 16, where the ascending vapor will be washed by the condensate collected thereon from the exchange drum 17 and the condenser drum 18. The condensate which is also scrubbed by the rising vapor causing the re-evaporation of the lighter fractions of the condensate, gravitates to the lower compartment 21, from whence it is conveyed from the drain pipe 30 to the proper storage tank.

The vapors leaving the rectifying tower enter the exchange drum 17, where an exchange of heat takes place between the vapors and the crude or charging oil on its

way to the still. The vapor then passes into the condenser or dephlegmator drum 18, where all the fractions heavier than a certain gravity are condensed, this separation being automatically controlled by the temperature regulating means, which governs the flow of cooling water around the tubes. This action is repeated in the following units to effect the separation of lighter fractions from the vapors of each succeeding unit. It will be noted that the flow of the vapors is counter-current to the flow of both the oil and the water. By this arrangement the cooling water will act successively upon vapors of a higher degree of temperature than the temperature of the preceding vapors, thereby permitting of the use of the same water to economize in the amount used. Likewise the crude or charging oil supply will be gradually tempered by meeting increasingly hotter vapors in the successive exchange drums.

In the modification illustrated in Figures 5, 6, and 7 of the drawings the rectifying tower 75 is provided with a plurality of vertically spaced horizontal baffle walls 76 which alternately terminate within the inner periphery of the tower at opposite sides thereof to compel the vapor or gas to travel through a sinuous course therethrough. The free ends of said baffle walls are provided with vertical upstanding and depending baffle flanges 77 and 78. The baffle walls 76 are further provided with a plurality of depending goose necks 79 which constitute gravity spray nozzles. By this arrangement the vapor condensate will gravitate through the goose necks and drop through the compartments 80 onto the next lower baffle wall 76 in the form of spray thereby bathing the vapor and gas as it passes throughout the rectifying tower. In this instance the rectifying tower is open at its upper end and is closed by the lower head 81 of the exchange drum 82. The upper head 83 and lower head 81 of the exchange drum are perforated for the reception of a battery of tubes 84 which establish communication between the upper compartment of the rectifying tower and a dephlegmator drum 85 which is open at its lower end and is secured over the head 83. The exchange drum is provided with horizontal baffle walls 86 which extend inwardly from opposite sides thereof to cause the crude oil passing therethrough to travel in a sinuous course from the intake pipe 87 to the outlet pipe 88. The dephlegmator drum 85 is provided with a bottom head 89 spaced from its lower end and an upper and inner head 90 which is covered by a supplemental head 91. The heads 89 and 90 are perforated for the reception of the battery of tubes 92 which establish communication between the upper and lower compartment 93 of the de-

phlegmator. The dephlegmator is provided with a plurality of horizontal baffle walls 95 which alternately extend inwardly from the opposite sides thereof to compel the water passing therethrough to travel in a sinuous course from the water intake pipe 96 to the outlet pipe 97. The remaining vapor in the compartment 93 is carried therefrom to the next unit by means of conduit pipe 98.

While there has been described and illustrated several preferred embodiments of the invention, it is to be understood that the right is reserved to others than those actually shown herein, to the full extent indicated by the general meaning of the terms in which the claims are expressed and by variations in the phraseology of the same.

I claim:

20. 1. In an apparatus of the character described, a distilling apparatus and a plurality of fractionating condensing units, arranged in series, the first unit communicating with the vapor space in the distilling apparatus, each unit comprising a heat exchanger and a water cooled condenser in communication with each other, with devices for drawing off condensate from each of said units; the arrangement being such that the vapors pass through each successive heat exchanger and water-cooled condenser in series, while the charging oil to the distilling apparatus flows in a countercurrent direction through each successive heat exchanger in heat absorbing relation to the vapors passing therethrough, the character of the condensate from each unit being governed by the flow of the cooling water through its respective condenser.
25. 2. In an apparatus of the character described, a distilling apparatus and a plurality of fractionating condensing units, arranged in series, the first unit communicating with the vapor space in the distilling apparatus, each unit comprising a heat exchanger and a water cooled condenser in communication with each other, with devices for drawing off condensate from each of said units; the arrangement being such that the vapors pass through each successive heat exchanger and water-cooled condenser in series, while the charging oil to the distilling apparatus flows in a countercurrent direction through each successive heat exchanger in heat absorbing relation to the vapors passing therethrough, the character of the condensate from each unit being governed by the flow of the cooling water through its respective condenser.
30. 3. In an apparatus of the character described, a distilling apparatus and a plurality of fractionating condensing units, arranged in series, the first unit communicating with the vapor space in the distilling apparatus, each unit comprising a heat exchanger and a water cooled condenser in communication with each other, with devices for drawing off condensate from each of said units; the arrangement being such that the vapors pass through each successive heat exchanger and water-cooled condenser in series, while the charging oil to the distilling apparatus flows in a countercurrent direction through each successive heat exchanger in heat absorbing relation to the vapors passing therethrough, the character of the condensate from each unit being governed by the flow of the cooling water through its respective condenser, and temperature controlling means actuated by the temperature of the vapors issuing from each unit for independently regulating the flow of said cooling water.
35. 4. In an apparatus of the character described, a distilling apparatus, and a plurality of units, arranged in series so that the first unit communicates with the vapor space of the distilling apparatus and delivers its residual vapors to the next in series, devices for returning condensate from said first unit to the still; the first unit comprising means whereby the vapors from the distilling apparatus are subjected to a bath in the charging oil; each unit comprising a heat exchanger and a water cooled condenser in communication with each other, with devices for drawing off condensate from each of said units; the arrangement being such that the vapors pass through each successive heat exchanger and water cooled condenser in series, while the charging oil to the distilling apparatus flows in a countercurrent direction through each successive heat exchanger in heat absorbing relation to the vapors passing therethrough, the character of the condensate from each unit being governed by the flow of the cooling water through its respective condenser.
40. 5. In an apparatus of the character described, a distilling apparatus, and a plurality of units, arranged in series so that the first unit communicates with the vapor space of the distilling apparatus and delivers its residual vapors to the next in series, devices for returning condensate from said first unit to the still; the first unit comprising means whereby the vapors from the distilling apparatus are subjected to a bath in the charging oil; each unit comprising a heat exchanger and a water cooled condenser in communication with each other, with devices for drawing off condensate from each of said units; the arrangement being such that the vapors pass through each successive heat exchanger and water cooled condenser in series, while the charging oil to the distilling apparatus flows in a countercurrent direction through each successive heat exchanger in heat absorbing relation to the vapors passing therethrough, the character of the condensate from each unit being governed by the flow of the cooling water through its respective condenser, and temperature controlling means actuated by the temperature of the vapors issuing from each unit for independently regulating the flow of said cooling water.
45. 6. In an apparatus of the character described, a distilling apparatus, and a plurality of units, arranged in series so that the first unit communicates with the vapor space of the distilling apparatus and delivers its residual vapors to the next in series, devices for returning condensate from said first unit to the still; the first unit comprising means whereby the vapors from the distilling apparatus are subjected to a bath in the charging oil, and means for controlling the temperature of vapors pass-

ing to the second unit, each unit comprising a heat exchanger and a water cooled condenser in communication with each other, with devices for drawing off condensate from each of said units; the arrangement being such that the vapors pass through each successive heat exchanger and water cooled condenser in series, while the charging oil

to the distilling apparatus flows in a countercurrent direction through each successive heat exchanger in heat absorbing relation to the vapors passing therethrough, the character of the condensate from each unit being governed by the flow of the cooling water through its respective condenser. .

ERNEST OWEN.
